(57) **CLAIM**

The ornamental design for a tubular food container, as shown and described.

DESCRIPTION

FIG. 1 is a side elevational view of tubular food container showing our new design; all other sides views being a mirror image thereof;

FIG. 2 is a top plan view thereof;

FIG. 3 is a bottom plan view thereof;

FIG. 4 is a side elevational view of an inner tray; shown separately for clarity;

FIG. 5 is a left side elevational view of FIG. 4;

FIG. 6 is a right side elevational view of FIG. 4;

FIG. 7 is a top plan view of FIG. 6;

FIG. 8 is a bottom plan view of FIG. 6; and,

FIG. 9 is an enlarged scale partial top perspective view thereof; with the inner tray partially received in the container body.
